ELECTRICAL CONNECTOR WITH CONTACT-PROTECTING AND ARC-QUENCHING SHIELD
 Daniel F. Daly, Newington, Conn., assignor to The Arrow-Hart & Hegeman Electric Company, Hartford, Conn., a corporation of Connecticut
 Filed Sept. 10, 1965, Ser. No. 486,300
 2 Claims. (Cl. 200—51.09)

This invention relates to connectors and, more particularly, to heavy duty electrical connectors for carrying current up to about 60 amperes up to about 250 volts D.C. or about 600 volts A.C.

Connectors of the sort to which this invention relates as heretofore made failed the Underwriters' tests requiring safe interruption of overloads a given number of times. For example, a connector to bear a 60 a., 600 v. D.C. or 250 v. A.C. rating should be able to withstand interruptions satisfactorily of a 90 ampere current. Often the arcs drawn between the contacts would jump to the metallic protective shell which was grounded, or the contacts burned away before the test was completed.

Therefore, one object of the invention is to provide an improved connector structure having superior arc quenching ability while preserving all the desirable attributes of prior heavy duty connectors.

Another object is to provide an improved wire terminal and grounding contact for such heavy duty electrical connectors.

Other objects and advantages will appear as the invention is described in connection with the accompanying drawing.

In the drawing:

FIG. 1 is a side elevation view, partly broken away and partly in section, of a plug and receptacle embodying the invention.

FIG. 2 is a view of the plug and receptacle parts of FIG. 1, partly broken away and partly in section, with the plug partly inserted in the receptacle.

FIG. 3 is a fragmentary perspective view of the faces of the receptacle and the plug.

FIG. 4 is a perspective view of the ground contact and terminal assembly used in the combination of the previous figures.

Referring to the drawing, the connecting device embodying the invention comprises a receptacle part and a plug part which has shoe contacts adapted to be engaged with contacts in the receptacle.

The receptacle and plug are each encased in a metal cylindrical protective shell 10, 10' open at one end and having an aperture at the opposite end for passage of an electric cable.

Each shell has a molded insulating liner in its inner end.

The receptacle is formed of a base 12 of insulating material to which is secured by rivets or other common means, a housing portion which also is of insulating material. The base 12 has a circular disc-like portion 14 on one side of which are mounted four identical equally spaced stamped sheet metal contacts such as 16, 17, 18 of L-shape. The longer or leg portions of these contacts are transversely arcuate while their feet are secured by rivets to the disc portion 14.

From the opposite side of the disc, a post 15 extends which is symmetrically longitudinally recessed to receive four identical conventional equally spaced heavy wire terminals such as 20, 21 capable of handling conductors for 60 ampere current. The post is also recessed longitudinally to receive a ground terminal and contact, designated generally by numeral 70, as hereinafter described.

Mounted on and secured by rivets, bolts or otherwise to the base 12 is a cylindrical hollow molded insulation housing portion 30 whose outside diameter is the same as that of the disc portion 14. The housing 30 surrounds and covers the receptacle contacts 16, 17, 18 and has recesses in its inner walls receiving said receptacle contacts.

The housing 30 has an opening in its end, above the tops of the receptacle contacts 16-18, in which is slidably mounted a closure member 40 in the form of a molded insulation disc having an irregular peripheral contour to fit into the complementary interior contour of the housing opening. The closure slides upon a pin 41 centrally positioned and fixedly mounted on the disc portion 14. Urging the closure constantly in position to close the opening in the housing and so as to cover and protect the receptacle contacts 16-18 is a coiled compression spring 43 impaled on the pin 41. One end of the spring rests on the disc portion 14 while the other presses against the inner surface of the closure.

The closure is stopped in its outward movement, under urge of the spring 43, by radial guides (not shown) abutting the outer ends of guide channels (not shown) formed in the inner surface of the housing part 30.

The plug member comprises an insulating body 50 having a disc-like central portion 51 and axial posts 54, 56 extending therefrom on opposite sides.

The inner post 54 has four symmetrically placed longitudinal recesses receiving four conventional wire terminals such as 60-62. The post also has a fifth longitudinal recess to receive a fifth wire terminal and grounding contact (not visible), as hereinafter described, for 5-wire usage.

The outer post 56 of the insulating body is cylindrical and has four contact shoes such as 66, 67, 68 mounted on lugs molded on the cylindrical surface at equally spaced positions and extending radially beyond the surface of the post. These contact shoes are each connected to one of the wire terminals by connections within the post and not visible. The outer face of each contact shoe is peripherally curved for rotative engagement with the respective receptacle contacts 16-18. Three of the shoes such as 66, 67 are of equal size; the fourth 68 is larger and positioned nearer the end of the post than the other three. (The fourth contact may be a ground contact in 4-wire usage.) Its different shape provides for polarity identity.

Since the contact shoes extend beyond the periphery of the plug post 56, grooves 35, 36, 37 are provided in the periphery of the opening in the receptacle housing part 30 for shoes 65, 66, 67 and a larger groove 38 for the larger or grounding contact shoe 68.

When the plug post 56 is placed against the closure 40 and pushed, the closure will be depressed permitting the post to enter the receptacle and permitting the contact shoes of the plug to engage receptacle contacts 16-18. The plug may then be rotated until the contact shoes have moved under the overhanging segments 31-34 of the top wall of the receptacle housing 30 between the grooves 35-38. The plug and receptacle parts of the connector will then remain connected together until reverse rotation occurs.

Cruciform ribs are formed in the face of the closure member 40 which engage in complementary cruciform grooves in the end portion 56e of the post 56. This engagement prevents inadvertent reverse rotation and popping out by the plug part after it has been connected with the receptacle part.

The foregoing describes a connector structure which has heretofore been used commercially. But heretofore the dimensions, thicknesses and spacings of the configurations of the parts resulted in too great travel of the closure inwardly before the plug contact shoes engaged

the receptacle contacts; and, conversely, when the plug contacts separated from the receptacle contacts, if current was flowing, arcing would result which persisted too long and caused excessive burning of the contacts and shortened contact life. In some cases, the arc would even jump to the metal protective shell, which was grounded, causing a short circuit. In other words, while the closure, when closed, covered the contacts and protected workers from touching the contacts, it did not satisfactorily perform as an arc quenching or extinguishing means.

To overcome this defect in the prior art, I have provided an annular recess or depression 42 in the outer face of the closure member 40 and have reduced the diameter of the end portion 56e of the plug post 56 so that it may enter the depression. This depression 42 creates an annular rim 44 on the closure so that the overall thickness of the closure need not be affected. Moreover, the upper or outer surface of this rim 44 is brought closer to the plug contact shoes than was their proximity to the surface of the closure heretofore.

In practice, as shown in the partly inserted position of the plug in FIG. 2, the rim 44 of the closure moves down and passes the level or plane of the tips of the receptacle contacts such as 16 and 18 with less travel and sooner than heretofore. Also, reversely, on withdrawal of the plug, the closure reaches the closing level (i.e. when the closure rim 44 reaches the plane of the underside of the overhanging segments 31-34) sooner than heretofore because it does not have to travel so far. From the foregoing, it is obvious that when the closure rim is at said closing level, a barrier of solid insulation (consisting of the closure rim 44 and closure 40 and the housing part 30 of the receptacle) exists between the receptacle contacts 16, 17 and 18 and the plug contacts 68, 66 and 67. The result is that connectors which heretofore failed Underwriters' overload interruption tests pass such test when my invention is embodied in them.

The closure acts effectively as an arc quenching and extinguishing means during closing as well as shielding the contacts and protecting workers against coming in contact therewith in the closed position of FIG. 1.

In 5-wire usage wherein one wire is for grounding the shell of the plug and receptacle parts of the connector, it is desirable to provide a smaller wire terminal. This should firmly grip a grounding wire and also engage a contact for flexibly and slidably engaging the shell. This makes it possible, after the wires are connected to the terminals, for the insulating body of the plug or of the receptacle to be slid quickly and easily into the protective metallic shell without hindrance or need for preliminary manipulation or adjustment.

As shown in FIG. 4, the terminal and contact structure has three parts. The basic terminal part is stamped from sheet metal as a rectangular strip which is then bent right angularly midway along its length forming two arms 71, 72 with narrowed tail 74 extending beyond the upstanding arm 72. One face of the tail, which may be considered the inner face, is serrated to afford a gripping surface to bite into and frictionally hold a conductor wire, as will more fully appear. The tail 74 receives a hollow rectangularly shaped box-like metallic clamping member 76 which is open at opposite ends and has a binding screw 77 in a tapped hole in the side thereof opposite the striated face 73 of the tail 74 when the clamp is impaled on the tail.

The terminal as thus far described is received in a recess in the post 15 of the receptacle and is secured therein by a rivet or other common securing means.

To electrically connect the terminal to the protective shell, a flexible contact stamped from thin sheet metal into substantially right angular shape has one of its legs 79 laid on the inner surface of the terminal arm 71 and secured thereto by the aforementioned rivet or other common securing means. The other leg 78 of the contact is

bent slightly outwardly from the periphery of the receptacle base 12. A shallow recess is molded in said periphery so that when the receptacle is slid into its shell, the leg 78 may bend inwardly into the recess as the leg engages slidably with the shell and makes electrical connection therewith. Thus, the shell may have a close fit with the receptacle due to the leg moving into the recess and slidably engaging the shell.

The same terminal and ground contact construction is used on the plug to ground its shell.

Modifications within the scope of the invention will occur to those skilled in the art. Therefore, the invention is not limited to the specific form illustrated and described.

What is claimed is:

1. An electrical connector comprising a receptacle having an insulating body with a central cavity extending into said body from one face and longitudinally extending channels in the walls of said cavity, receptacle contacts in said channels, a slidable closure of insulating material in said cavity having radial extensions entering said channels, means biasing said closure outwardly in position to close the entrance to said cavity, a recess in the outer face of said closure providing a peripheral rim around said outer face, the outer surface of said rim being coplanar with said one face of said insulating body, in combination with a plug member of insulating material having a central post configured to enter said central cavity when pressed against said closure, plug contacts on the periphery of said post position to slide within said channels as said post is inserted in said cavity, means on said plug member and said receptacle body interlocking upon relative twisting of said member and body to hold the two together, the end of said post being reduced in size and configured to fit within said recess in said closure and to be turnable therein, said recess and said reduced end lessening the distance that the plug contacts must move to engage the receptacle contacts after the plug engages the closure, and also lessening the distance that said rim must travel to provide a solid insulation barrier, as compared with the same distances of travel when the plug end is not reduced and there is no recess for it in said closure for a reduced plug end, said closure and insulating body cooperating to provide said barrier and to quench arcing between the plug and receptacle contacts as they separate.

2. A ground wire terminal and contact construction in combination with an insulating connector body and a metallic protective shell around said body, said terminal and contact construction comprising a stamped sheet metal member having two arm portions at a right angle to each other, a finger extending from one of said portions, a hollow tubular clamping member embracing said finger, means on said clamping member to clamp a wire against the surface of said finger, said hollow clamping member and said stamped member being received in a recess in said insulating body, a flexible contact member having two legs bent at approximately right angles to each other, and means to secure one leg thereof against the second of said arm portions upon the insulating body with the other of said legs in position to resiliently engage said shell.
